UNITED STATES PATENT OFFICE.

CHARLES M. NEISS, OF NEWARK, NEW JERSEY.

COLLAR-BUTTON.

1,286,067.

Specification of Letters Patent. Patented Nov. 26, 1918.

Application filed December 29, 1917. Serial No. 209,547.

To all whom it may concern:

Be it known that I, CHARLES M. NEISS, a citizen of the United States, residing at Newark, in the county of Essex and State 5 of New Jersey, have invented new and useful Improvements in Collar-Buttons, of which the following is a specification.

This invention relates to a button which is primarily intended to be used at the back 10 of a shirt band to secure a collar thereto, although the construction of the button is such that it may be advantageously employed in other places and for other purposes if desired.

15 The primary object of the invention is to provide a button of this character which not only enables the collar to be easily applied or removed from the shirt band with one hand, but is so constructed that the collar cannot slip from the button while the 20 ends of the collar are being buttoned to the front of the shirt band.

Another object of the invention is to provide the button with a shank and head 25 which will not offer opposition to movement of the tie between the folds of the collar after the collar has been applied to a shirt band.

Another object of the invention is to provide 30 the button with a head, one side of which is provided with a pair of oppositely inclined faces which enable the head to be readily passed through the button hole in a shirt band or collar.

35 A further object of the invention is to provide the button with a head which is curved to conform to the curvature of the collar and shirt band, thus preventing the neck of the wearer of the collar from becoming 40 chafed by the head of the button.

With these and other objects in view, the invention resides in the novel combination and arrangement of parts which will be hereinafter described and particularly pointed 45 out in the claim.

In the drawing:

Figure 1 is a prespective view of a collar button constructed in accordance with the invention.

50 Fig. 2 is a sectional view showing the button in applied position.

Figs. 3, 4 and 5 are views of the button

in applied position with the outer fold of the collar broken away.

Fig. 6 is a section on the line 6—6 of 55 Fig. 2.

Like characters of reference denote the corresponding parts throughout the several views in the drawings.

Referring now to the drawings in detail 60 the letter A designates a portion of a shirt band with which is connected a portion of a collar B by means of a button C constructed in accordance with the invention.

The button C includes a substantially rectangular shaped plate or base 10 which is curved longitudinally throughout its length and has the corners thereof beveled.

The base or plate 10 is provided centrally of its convex face with an outwardly extending stem. The stem comprises a horizontally extending portion 11 which may be formed integral with the plate 10 if desired, and a reduced and curved portion 12 which provides the stem between its ends with 70 shoulders 13. The opposite side edges of the horizontally extending portion of the stem 11 are curved to prevent the ends of the button hole being cut by the stem, while the shoulders 13 prevent the collar B from being 75 forced on to the horizontally extending portion of the stem while the button is in use.

The outer end of the extension 12 has formed integral therewith a head 14 which projects beyond the opposite side edges of the extension 12 and is curved longitudinally throughout its length to correspond to the curvature of the neck band and collar to which the button is applied. The upper side edge of the head 14 is beveled upon opposite sides of the extension 12 to facilitate the passage of the head through the button holes in the shirt and collar.

By providing the button with a stem and head constructed as above described it is 95 obvious by reference to Figs. 4 and 5 in the drawing that when the button is employed to connect a collar with the back of a shirt band the collar cannot slip from the button while the ends of the collar are being buttoned to the front of the band.

When the button has been applied to a shirt band and it is desired to connect the collar with the shirt band by means of the

button, the inner fold of the collar is held between the thumb and forefinger of one hand. One of the ends of the head 14 which project beyond the curved portion of the 5 stem of the button is now passed through the button hole in the collar after which, the other end of the head is passed through the button hole, the beveled faces on the head facilitating the passage of the head through 10 the slit in the inner fold of the collar.

When the collar has been applied to the shirt band in the manner above described the curved portion of the stem not only spaces the folds of the collar a sufficient distance apart to allow the tie to be easily slid therebetween, but also positions the head 14 below the button hole, so that the head and stem offer no opposition to the sliding of the tie between the folds of the collar.

20 From the foregoing description taken in connection with the accompanying drawings it is apparent that a button for collars

has been provided which though inexpensive of manufacture is highly efficient for the purposes stated.

Having thus described the invention what is claimed as new, is:

A collar button comprising a rectangular shaped plate curved longitudinally throughout its length, a central stem on the convex 30 side of said plate having a horizontally extending portion and a reduced portion curving downwardly and outwardly from said horizontally extending portion, an elongated head at the outer end of said curved portion 35 projecting beyond opposite sides thereof and curved longitudinally throughout its length, and faces on said head inclining downwardly and outwardly from said reduced curved portion of the stem to the ends of 40 the head.

In testimony whereof I affix my signature.

CHARLES M. NEISS.
